UNITED STATES PATENT OFFICE.

EDWARD VROOM, OF OSSINING, NEW YORK, ASSIGNOR TO WESTERN ELECTRIC COMPANY, INCORPORATED, OF NEW YORK, N. Y., A CORPORATION OF NEW YORK.

DESIGN FOR A LOOP ANTENNA.

Application filed May 24, 1924. Serial No. 9,698. Term of patent 14 years.

To all whom it may concern:

Be it known that I, EDWARD VROOM, a citizen of the United States, residing at Ossining, in the county of Westchester and State of New York, have invented a new, original, and ornamental Design for Loop Antennæ, of which the following is a specification, reference being had to the accompanying drawings, forming a part thereof.

Fig. 1 is a view in perspective of a loop antenna embodying a new and improved design.

I claim:

An ornamental design for a loop antenna as shown.

In witness whereof, I hereunto subscribe my name this 23rd day of May, A. D., 1924.

EDWARD VROOM.
